UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

PRESSURE FLUID MOTOR

Application filed June 4, 1927. Serial No. 196,431.

This invention relates to pressure fluid motors and more particularly to pressure fluid motors of the hammer type.

An object of this invention is to provide an improved pressure fluid motor. Another object is to provide an improved pressure fluid motor of the piston-controlled valve type having improved and simplified fluid distribution means. Another object of this invention is to provide an improved pressure fluid motor having improved fluid distribution means wherein the fluid distribution valve is thrown by compression. A further object is to provide an improved pressure fluid motor having improved and simplified fluid distribution means whereby the power and efficiency of the motor is materially increased. These and other objects and advantages of this invention will, however, hereinafter more fully appear.

In the accompanying drawing there is shown for purposes of illustration one form and a modification thereof which the invention may assume in practice.

25 In this drawing,—

Fig. 1 is a central longitudinally extending sectional view illustrating the improved pressure fluid motor.

Fig. 2 is a view similar to Fig. 1 illustrating 30 the motor piston and distribution valve in different positions.

Fig. 3 is a detail sectional view illustrating a portion of the improved fluid distribution means.

35 Fig. 4 is an enlarged elevational view of the distribution valve.

Fig. 5 is a view similar to Fig. 2 illustrating a modified form of construction.

In the illustrative construction shown in 40 Figs. 1 to 4 the invention is shown embodied in a pressure fluid motor of the hammer type comprising a cylinder 1 having a bore 2 in which is reciprocably mounted a hammer piston 3. The piston 3 has formed integral therewith a forwardly projecting extension or striking bar 4. As shown, suitably secured within a bore 5 formed within the forward end of the cylinder 1 is a buffer ring 6 having a central opening 7 within which the striking bar 4 is adapted to enter. The rear end of

the cylinder bore 2 is closed by a combined head block and valve chest 8 housed within a bore 9 formed within a rear head member 10. Interposed between the member 10 and the head block 8 is a rear plate 11. The buffer ring 6, cylinder 1, head block 8, rear plate 11 and rear head member 10 are held in assembled relation in any suitable and convenient manner.

The improved fluid distribution means 55 comprises aligned bores 12 and 13 of different diameters having their axes aligned with the longitudinal axis of the motor cylinder. As shown, the rear plate 11 has formed thereon a forwardly projecting cylindrical boss 14 60 which fits the bore 12 and this plate is provided with a central opening 15 extending therethrough and communicating with a chamber 16 formed within the rear head member 10. The forward end of the bore 13 65 communicates with the rear end of the cylinder bore 2 through a central opening 17. In accordance with the illustrative embodiment of the invention shown in Figs. 1 to 4 an automatic fluid distribution valve 18, herein 70 preferably of the two-spool differential type, is reciprocably mounted in the valve chamber and is provided with an enlarged spool 19 fitting the bore 12 and a reduced front end spool 20 fitting the bore 13, the 75 spools 19 and 20 being connected by an intermediate reduced portion 21. The valve 18 is made hollow substantially throughout its length as at 22 for the purpose of materially reducing the weight thereof. The valve 18 80 is also provided with a cylindrical projection 23 formed on the rearward end thereof and this projection fits the opening 15 in the rear plate 11. The valve 18 is also provided with a cylindrical portion 24 formed thereon at 85 the forward end of the enlarged spool 19 and this portion is adapted to fit the bore 13 and is of the same diameter as the end spool 20. Pressure fluid is adapted to be supplied to the motor through a supply passage 25 90 which communicates with a passage 26 under the control of a usual manually operable throttle valve 26^a. The passage 26 communicates with the chamber 16 which is herein 95 a constant pressure chamber. The pressure 100

in the chamber 16 acts continuously on the rear pressure area of the cylindrical projection 23 of the distribution valve. Pressure fluid flows from the chamber 16 through an opening 27 formed in the rear plate 11 (see Fig. 3) and through a longitudinal passage 28 formed in the head block 8 into an annular recess 29 formed within the valve chest adjacent the forward end of the bore 13. Also communicating with the bore 13 intermediate the front spool 20 and the cylindrical portion 24 is a laterally extending passage 30 which communicates through a passage 31 with a longitudinally extending supply passage 32 formed in the motor cylinder and this passage communicates by a lateral port 33 with the forward end of the cylinder bore 2. Extending laterally directly through the side wall of the cylinder intermediate the ends thereof are parallel piston controlled exhaust ports 34 and 35 through which the exhaust motive fluid from the opposite ends of the cylinder is adapted to flow as will later be described. Communicating with the cylinder bore at a point substantially intermediate the rear end thereof and the port 34 is a lateral port 36 which communicates, through throwing passages 37 and 38 formed in the cylinder and head block respectively, with the rear end of the bore 12. Communicating with the bore 12 adjacent the forward end thereof and extending laterally through the head block 8 and head member 10 is an exhaust passage 39. In this instance the valve 18 has formed therein a radial leak port 40 extending through the spool 20 and connecting the annular recess 29 with the interior of the valve, pressure fluid being adapted to leak continuously through this port for a purpose to be hereinafter described.

In the modified construction shown in Fig. 5 an automatic fluid distribution valve 41 is employed having reduced cylindrical end portions 42 and 43 respectively slidably mounted in the bore 15 in the plate 11 and in a bore 44 formed in the head block 8. This valve is also provided with enlarged end spools 45 and 46 connected by a reduced intermediate portion 47, these spools fitting a bore 48 similar to the bore 13 heretofore described. Communicating with the bore 48 are the passages 30, 38 and 39 and the annular recess 29, these passages and recess being the same as those of the preferred form. Connecting the forward end of the bore 48 with the rear end of the cylinder bore 2 is a longitudinal passage 49 located laterally of the bore 44, this passage taking the place of the central passage 17 described above. The bore 44 at the forward end of the valve is vented to atmosphere through a small leak port 50.

In the operation of the improved pressure fluid motor shown in Figs. 1 to 4 it will be assumed that the hammer piston 3 is in the position shown in Fig. 2 and is about to be

driven forwardly. At this time pressure fluid flows from the passage 25 through passage 26, chamber 16, port 27, passage 28, through the annular recess 29, past the forward surface of the front spool 20 and through the central opening 17 directly into the rear end of the cylinder bore. At the same time the pressure fluid within the forward end of the cylinder bore is exhausted through ports 34, 35 and through port 33, passage 32, passage 31, port 30, through the bore 13 and thence through the exhaust port 39 directly to atmosphere. Resultantly, the pressure fluid within the rear end of the cylinder bore acts on the pressure area on the piston and the latter is driven forwardly to effect its working stroke. As the hammer piston 3 moves forwardly the port 36 is uncovered and pressure fluid is admitted from the rear end of the cylinder bore through port 36 and the passages 37 and 38 to the bore 12 in the valve chest, the fluid acting on the rear surface of the enlarged spool 19, which, together with the constant pressure acting on the cylindrical projection 23, causes the valve 18 to be thrown forwardly from the position shown in Fig. 2 to the position shown in Fig. 1. As soon as the valve moves to this position the rear end of the cylinder is open to exhaust by way of passages 37 and 38, bore 12 and passage 39, but the piston has moved a considerable distance before a substantial quantity of fluid escapes in this manner due to the time required to actuate the valve and because of the restricted character of the passages. When the valve is in the position shown in Fig. 1 the supply of pressure fluid from the recess 29 flowing through the central passage 17 is cut off by the end spool 20. However, the hammer piston 3 continues its forward movement due to the expansive action of the pressure fluid and momentum until it reaches the extreme end of its working stroke. As the hammer piston overruns the ports 34 and 35 the pressure remaining within the rear end of the cylinder bore is exhausted directly to atmosphere. After the valve is thrown to the position shown in Fig. 1 the pressure acting on the rear surface of the enlarged spool 19 is vented directly to atmosphere through the passage 39 and the valve is held in the position shown only by the constant pressure acting on the cylindrical projection 23 on the valve. At the same time pressure fluid flows from the chamber 16 through passage 28, annular recess 29, through the bore 13 past the rearward surface of the spool 20 through lateral port 30, passage 31, passage 32 and lateral port 33 to the forward end of the cylinder bore and the pressure fluid acting on the forward pressure area of the piston drives the latter rearwardly. As the hammer piston 3 moves rearwardly, the ports 35 and 34 are uncovered and the forward end of the cylinder bore is

opened to exhaust and as the piston continues its rearward movement the port 36 is closed and the air continuously flowing through the leak passage 40 is trapped within the rear end of the cylinder bore and is highly compressed, and as a result, the valve 18 is thrown rearwardly by compression against the continuous pressure acting on the relatively small area on the projection 23. The cycle of operation described above is repeated during the normal operation of the motor.

The operation of the modified construction shown in Fig. 5 is substantially the same as that described above. When the valve 41 is in the position shown in Fig. 5 pressure fluid flows from the chamber 16 through passage 28 to the annular recess 29 and thence through passage 49 to the rear end of the cylinder bore and as a result the hammer piston 3 is driven forwardly to effect its working stroke. The forward end of the cylinder bore is opened to exhaust through the piston controlled ports 34 and 35 and also through passages 32, 31, and 30, through the bore 48, between the spools 45, 46 on the valve, and past the forward surface of the spool 45 and through passage 39 to atmosphere. As the hammer piston moves forwardly the port 36 is uncovered and fluid flows through port 36 and passages 37 and 38 to the bore 48 at the rear side of the spool 45, the pressure acting on this spool together with a constant pressure in the chamber 16 acting on the projection 42, throwing the valve 41 forwardly thereby closing the exhaust passage 39 and cutting off fluid flow from the recess 29 through the passage 49 to the rear end of the cylinder bore. At the same time the passage 30 is connected with the recess 29 and fluid then flows through this recess past the rear surface on the spool 46, through the bore 48, through passages 30, 31 and 32 and through port 33 to the forward end of the cylinder bore. The pressure within the rear end of the cylinder bore is exhausted through ports 34 and 35 and also through ports 36, passages 37 and 38, through the bore 48 past the rear surface on the spool 45 and through passage 39 to atmosphere. The hammer piston is then driven rearwardly by the fluid flowing through port 33. As the piston moves rearwardly ports 34, 35 and 36 are closed and the pressure fluid trapped within the rear end of the cylinder is compressed, and as the forward end of the bore 48 is always in communication with the rear end of the cylinder bore, the pressure acting on the forward surface of the spool 46 is built up and the valve is thrown rearwardly against the opposing pressure acting on the projection 42. The above cycle of operation is repeated throughout the normal operation of the motor.

While I have in this application specifically described one form and a modification thereof which the invention may assume in

practice, it will be understood that this form and modification of the same are shown for purposes of illustration and that the invention may be modified and embodied in various other forms without departing from its spirit or the scope of the appended claims.

What I claim as new and desire to secure by Letters Patent is:

1. A pressure fluid motor comprising a cylinder, a piston reciprocable therein, and fluid distribution means for effecting reciprocation of said piston comprising a reciprocable differential valve having an end area in constant communication with the rear end of the cylinder whereby the valve may be thrown in the rearward direction by compression pressure built up in the rear end of the cylinder on the return stroke and means for throwing the valve in the opposite direction on the forward stroke of the piston before the rear end of the cylinder is opened to exhaust, said valve being hollow and having a closed reduced rear end subjected to constant pressure for holding the valve in said latter position.

2. A pressure fluid motor comprising a cylinder, a piston reciprocable therein, and fluid distribution means for effecting reciprocation of said piston including a reciprocable differential valve arranged coaxially with and at the rear end of said cylinder, a direct axial passage for placing a forwardly facing surface of said valve in constant communication with the rear end of said cylinder whereby the valve may be thrown in the rearward direction by compression pressure, and means for throwing the valve in the opposite direction on the forward stroke of the piston before the rear end of the cylinder is opened to exhaust, said valve being hollow and having a closed end subjected to constant pressure for holding the valve in said opposite position.

3. A pressure fluid motor comprising a cylinder, a piston reciprocable therein, and fluid distribution means for effecting reciprocation of said piston including a reciprocable valve arranged coaxially with and at the rear end of said cylinder, a direct axial passage for placing a forwardly facing surface of said valve in constant communication with the rear end of said cylinder whereby the valve may be thrown rearwardly by compression pressure in the rear end of said cylinder, means providing a restricted leak passage between the rear end of the cylinder and the supply when the valve is in its forward position, and means for throwing the valve in the opposite direction on the forward stroke of the piston before the rear end of the cylinder is opened to exhaust comprising a rearwardly facing area subjected to constant pressure, a second rearwardly facing area and a piston controlled passage for subjecting said second area to intermittent pressure.

4. A pressure fluid motor comprising a cyl-

inder, a piston reciprocable therein, and fluid distribution means for effecting reciprocation of said piston including a reciprocable differential valve having an end spool for controlling admission of motive fluid to the rear end of the cylinder past an end of the valve, a passage for placing a forwardly facing surface on said valve in constant communication with the rear end of the cylinder whereby the valve may be thrown rearwardly by compression pressure in the rear end of the cylinder, and means for throwing the valve in the opposite direction on the forward stroke of the piston including a larger spool on said valve and a piston controlled passage for admitting throwing pressure to said spool before the rear end of the cylinder is opened to exhaust, said valve being hollow and having a reduced closed rear end subjected to constant pressure.

5. A pressure fluid motor comprising a cylinder, a piston reciprocable therein, and fluid distribution means for effecting reciprocation of said piston comprising a valve chest in axial alinement with said cylinder, a reciprocable differential valve in said valve chest, a direct axial passage for placing a forwardly facing surface of said valve in constant communication with the rear end of said cylinder whereby the valve may be thrown rearwardly by compression pressure, said valve having an end spool controlling admission of live fluid to both ends of said cylinder, a smaller guiding portion at the rear end of said valve subjected to constant pressure, an enlarged spool disposed intermediate the ends of said valve and which controls exhaust means for both ends of the cylinder and a piston controlled passage opening on the forward stroke of the piston before the rear end of the cylinder is opened to exhaust for conducting pressure fluid to the rear surface of said large spool for throwing the valve in the forward direction.

45. 6. A pressure fluid motor comprising a cylinder, a piston reciprocable therein, and fluid distribution means for effecting reciprocation of said piston comprising a valve chest, a reciprocable valve therein having a single spool arranged in cooperation with passages in said chest to control admission to both ends of the cylinder, and a closed end formed to constitute a reduced portion which is at all times maintained within a correspondingly reduced bore in said chest, said valve also having an enlarged spool intermediate the ends thereof, a piston controlled passage for subjecting said intermediate spool to pressure for throwing said valve to one position, and means for subjecting said reduced end to constant live pressure to assist in throwing the valve and holding the same in said position.

65. 7. A pressure fluid motor comprising a cylinder, a piston reciprocable therein, and fluid

distribution means for effecting reciprocation of said piston comprising a reciprocable hollow valve arranged in the rear end of the cylinder and having a single spool controlling admission to both ends of said cylinder, a reduced closed opposite end disposed at all times within a reduced bore, and an enlarged spool intermediate the end of said valve, a piston controlled passage for subjecting said large spool to pressure for throwing the valve to one position, and means for subjecting said reduced end to constant live pressure to assist in throwing the valve and holding the same in said position, said valve having means for controlling exhaust from the front end of the cylinder.

8. A pressure fluid motor comprising a cylinder, a piston reciprocable therein, and fluid distribution means for effecting reciprocation of said piston comprising a reciprocable valve arranged coaxially with the cylinder and having a forward end spool arranged to control admission to both ends of the cylinder, an enlarged spool intermediate the ends of said valve, and a closed reduced rear end disposed at all times within a reduced bore whereby pressure fluid is prevented from flowing past said closed end, a piston controlled passage for subjecting said intermediate spool to pressure for throwing the valve forwardly, and means for subjecting the reduced rear end to constant live pressure.

9. A pressure fluid motor comprising a cylinder, a piston reciprocable therein, and fluid distribution means for effecting reciprocation of said piston comprising a reciprocable valve arranged coaxially with the cylinder and having a forward end spool arranged to control admission to both ends of the cylinder, an enlarged spool intermediate the ends of the valve, and a closed reduced rear end disposed at all times within a reduced bore whereby pressure fluid is prevented from flowing past said closed end, a piston controlled passage for subjecting said intermediate spool to pressure for throwing the valve forwardly, means for subjecting the reduced rear end to constant live pressure, and means providing a restricted leak passage for placing the rear end of the cylinder in communication with the supply when the valve is in its forward position.

10. A pressure fluid motor comprising a cylinder, a piston reciprocable therein, and fluid distribution means for effecting reciprocation of said piston comprising a valve chest, an exhaust passage leading therefrom, a valve reciprocable in said valve chest having an end spool controlling admission to both ends of the cylinder, an annular groove formed in said valve adjacent said spool for alternately connecting the front end of the cylinder to supply and to said exhaust passage, an enlarged spool controlling exhaust from both ends of said cylinder, and a piston controlled

passage for subjecting said enlarged spool to fluid pressure for throwing the valve in one direction.

11. A pressure fluid motor comprising a cylinder, a piston reciprocable therein, and fluid distribution means for effecting reciprocation of said piston comprising a valve chest, an exhaust passage leading therefrom, a reciprocable valve in said valve chest having a single spool controlling admission to both ends of said cylinder, an annular groove adjacent said spool and alternately connecting the front end of the cylinder to supply and to said exhaust passage, a second spool having an intermediate shoulder adjacent said groove to control exhaust for the front end, and an enlarged portion arranged to control communication between the rear end of the cylinder and said exhaust passage, and a piston controlled passage for subjecting said enlarged portion of the spool to fluid pressure for throwing the valve in one direction.

12. A pressure fluid motor comprising a cylinder, a piston reciprocable therein, and fluid distribution means for effecting reciprocation of said piston comprising a valve chest, an exhaust passage leading therefrom, a valve reciprocable in said valve chest having a spool controlling admission to both ends of the cylinder, said spool having an area in constant communication with the rear end of the cylinder, an annular groove formed in said valve adjacent said spool for alternately connecting the front end of the cylinder to supply and to said exhaust passage, a second spool controlling exhaust from both ends of said cylinder, means of larger area than said first mentioned area adapted to be subjected to pressure for throwing the valve in one direction including an area on said second spool, and a piston controlled passage for subjecting said area to pressure in the cylinder.

In testimony whereof I affix my signature.
ELMER G. GARTIN.
